UNITED STATES PATENT OFFICE.

WILLIAM WINFIELD SIMPSON, OF SEWICKLEY, PENNSYLVANIA.

METHOD OF DISPLAYING COLLAPSIBLE TUBES.

Application filed March 26, 1921. Serial No. 455,847.

To all whom it may concern:

- Be it known that I, WILLIAM WINFIELD SIMPSON, a citizen of the United States, residing at Sewickley, in the county of Allegheny and State of Pennsylvania, have invented a new and useful Improvement in Methods of Displaying Collapsible Tubes, of which the following is a full, clear, and exact description.
- 10 The present invention relates to displaying collapsible tubes. This has for its object the displaying of collapsible tubes for advertising purposes, etc., for example, in show cases and on counters.
- 15 In the drawings which illustrate the preferred embodiment of the invention,

Figure 1 is an elevation of the display standard;

Figure 2 shows the display standard with 20 a tube on it, and

Figure 3 is an elevation of the collapsible tube itself.

Referring to the illustrated embodiment of the invention, the display standard consists 25 of a cylindrical form 1 which fits into the tube, and a base 2 for holding the standard upright. The form 1 is of the same length as the tube. It keeps the tube displayed on it from being collapsed or dented. The tube 30 3, which is to be displayed, has its bottom end left unsealed and open so that it can be readily slipped over the display standard, the upper end of the latter having a conical form similar to that of the upper end por-

tion of the tube to be displayed and serving 35 to initially spread the lower end of the tube in the application of said tube to said standard.

The display standard holds the tube upright and from being collapsed or dented 40 and makes an attractive advertising display. The display standard with the tube on it may also be used for other purposes such, for example, as a paper weight. The display standard may be made of any suitable 45 material such, for example, as wood or pressed metal. The tubes which are to be displayed are the ordinary metallic collapsible tubes such as are used for holding shaving cream, tooth paste, etc.

The present invention is not limited to its illustrated embodiment but may be otherwise embodied within the scope of the following claim.

I claim:

55 The method of displaying collapsible tubes which consists in leaving the tube empty with its lower end unsealed and open, and placing such tube on an upright display standard having a form which initially 60 spreads the lower open end of the tube and which fills the interior of the tube and supports it in display position, substantially as described.

In testimony whereof, I have hereunto 65 set my hand.

WILLIAM WINFIELD SIMPSON.
